Design No. 18,207, dated March 27, 1888.

UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,207, dated March 27, 1888.

Application filed January 11, 1888. Serial No. 260,447. Term of patent 3½ years.

To all whom it may concern:

Be it known that I, JENNIE SHEILS, of the city, county, and State of New York, have invented and produced a new and original Design for a Pattern of a Lady's Costume with Back Drapery and Train; and I do hereby declare that the engraved prints accompanying this specification convey to any one accustomed to using paper patterns a clear understanding 10 of how a garment made up by the pattern will appear.

The design shows a basque and round skirt. The skirt exhibits a long drapery on the left side gore that displays spaced draping plaits 15 in its front and back edges, a flat drapery extending from this drapery to the right side back seam, and falling in kilt plaits at either

side edge, a long pointed tablier that displays numerous plaits in its upper and side edges, and a full back drapery that falls even all across 20 the bottom edge. The basque displays a deep point at the center of the front and back, plaited surplices, a standing collar, and elbow-sleeves.

What I claim as my invention, and desire to 25 secure by Letters Patent, is—

The design for a lady's costume with back drapery and train, as shown in the engraved prints accompanying this specification.

JENNIE SHEILS.
